UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO, A CORPORATION OF OHIO.

CAR-COUPING.

1,194,109.

Specification of Letters Patent. Patented Aug. 8, 1916.

Application filed August 30, 1910. Serial No. 579,686.

To all whom it may concern:

Be it known that I, JOHN WILLISON, a subject of the King of Great Britain, residing at Derby, in the county of Derby, England, have invented a new and useful Improvement in Car-Couplings, of which the following is a full, clear, and exact description, reference being had to the accompanying drawings, forming part of this specification, in which—

Figure 1 is a front elevation showing a preferred form of my improved car coupler; Fig. 2 is a longitudinal section showing the coupler in locked position; Fig. 3 is a view similar to Fig. 2, showing the lockset position; Fig. 4 is a sectional top plan view with the parts in locked position; Fig. 5 is a view similar to Fig. 4, illustrating the opening of the knuckle, and showing a shorter guard arm; Fig. 6 is a cross section on the line VI—VI of Fig. 4, showing the lockset position in dotted lines; Fig. 7 is an inverted plan view of the knuckle, showing the knuckle-thrown position in dotted lines; and Fig. 8 is a detail view showing the knuckle pin support.

My invention relates to the class of car couplers and is designed to provide a simple form of car coupler which will perform all the desirable functions of locking and unlocking, locksetting, and knuckle-throwing, without complication or the use of small fragile parts.

In carrying out my invention, the lock and the knuckle thrower are formed as separate elements, and the knuckle thrower, in addition to its function of throwing the knuckle, acts to lift the lock to lockset position in the initial movement of said knuckle thrower. The lock is taken off the lockset shelf or ledge by the outward movement of the knuckle, and is supported on the knuckle until the knuckle has closed. In its function of lifting the lock to lockset position, the knuckle thrower acts as a lever, while in its knuckle throwing function, it acts as a pulling rod.

In the drawings, 2 represents the coupler head, 3 the knuckle, and 4 the knuckle pin. The numeral 5 designates the knuckle tail, which is preferably provided with a horn 6, projecting into a recess of the head, to assist in resisting the pulling strain. The wall 7 of the coupler head, which receives the horn, is slightly spaced apart from the

rounded rear surface of the tail and horn, except in that portion of the wall which is in the rear of and substantially in line with the knuckle pin 4. Here the knuckle tail and the wall are shaped to fit against each other snugly, thus taking the shocks of buffing. In order to provide for variations in the parts, the pin is preferably made slightly smaller than the hole in the knuckle.

The locking block 8 moves vertically and its shape is well shown in Figs. 2, 3 and 4. Its outer face fits the wall of the head, while its inner face fits against the corresponding face of the knuckle tail, these faces being substantially parallel. The head portion of this piece forms the locking block proper, while the remainder forms a depending leg 9, having a forward projection 10, which acts as a lock-to-the-lock or anticreeping device. The forward portion of the head is provided with a depending portion 11, and the rear upper part of the head is slightly beveled, as shown at 12, to allow the lock to tilt into the locking position shown in Fig. 2. In this position, the lug 10 enters a recess 13 in the forward wall of the head which accommodates the leg portion 9 of the locking block. When lifted, the head of the locking block enters a pocket 14, formed in the top portion of the coupler head.

To move the locking block out of its locked position and lift it to the rear lockset ledge of the coupler, shown at 15, I use the knuckle opener 16, which is preferably a bar or rod, having its inner end bent or hooked around, as shown at 17, to engage a downward projection on the knuckle tail, this projection having a recess to receive the shank of the opener. The bottom portion of the coupler is preferably formed with a downwardly inclined pocket 18, within which the lever can swing, being preferably actuated by a chain 19, pivotally connected to its outer projecting end.

Under the strain of the chain, the first action is to lift the outwardly projecting end of the knuckle opener and cause it to act upon the forwardly beveled face 20 at the bottom of the locking block leg, thus releasing the lock-to-the-lock in two ways: first, by acting on the beveled face; and second, by taking the weight of the lock on the opener, thus causing the leg to move backwardly, on account of its forwardly overhung head. As the tilting movement of

the lever progresses, the lock will be lifted, and at the same time, a tendency to a rearward movement imparted thereto until it reaches the lockset shelf or ledge 15, when 5 its leg will be moved back on to said ledge by the two actions above described, namely, the action of the lever on its beveled face and the gravity action of its overhung head. If the knuckle is now pulled open, as by the 10 drawing away of an opposing car coupled therewith, the rib 5^a on its tail will engage the depending flange on the head of the lock and at the same time, the inclined surface of the tail inside the rib will act on the bottom 15 of the flange or projection 11. The rib, therefore, will tend to pull the lock forwardly off its lockset seat, and at the same time, the weight being taken on the inclined top face portion of the tail, this will also 20 act to cause the leg to be brought forwardly. Both of these actions will draw the lock off the lockset shelf and further motion of the knuckle will hang it up on the knuckle, where it remains during the opening of the 25 knuckle. On the inward movement of the knuckle tail, the lock will move downwardly slightly within its pocket until the tail has passed it, when it will drop down into the locking position shown in Fig. 2. If, after 30 locksetting, the motion is continued to throw the knuckle open, the further pull on the chain will then cause the hook 17 of the knuckle opener to throw the knuckle open by direct pull on its tail. In this case, the 35 lock is again lifted in the same manner as before, and remains hung on the knuckle tail until the knuckle is closed, when the lock again drops into the position of Fig. 2, in which it locks the knuckle and is itself 40 locked against displacement by shocks or jars.

The chain 19 preferably extends upwardly to the side of the coupler, and thence through a guide 21 to the crank arm 22 of 45 the operating lever. To support the knuckle pin, I provide a dovetail or undercut slot in the wall of the lower ear 23, into which is slipped a pin support 24, which is shaped to be locked in said recess by the insertion of 50 the pin from above. This support has a pin-carrying extension 24^a under the pin to support the latter, and is effectively held in place by the pin itself.

The advantages of my invention will be 55 obvious to those skilled in the art. The parts are simple, few in number and easy to make and assemble. There is little or no machining of the parts required, and they are large and heavy and not liable to 60 breakage. All of the desirable functions of the modern coupler are afforded, and a positive motion imparted by the pull of the knuckle opener, instead of acting through a cam or similar device.

65 Many changes may be made in the form

and arrangement of the head, the knuckle, the locking block, opener, etc., without departing from my invention as defined in my claims.

I claim:

1. In a coupler, a head, a knuckle having a tail, a vertically movable and tilting locking block having a lock-to-the-lock engagement with the coupler head when in locked position, and a tilting and endwise bodily movable pulling lever having hooked engagement with a knuckle tail within the coupler cavity, said pulling lever extending underneath the locking block, the lever and block being shaped to tilt the locking block 75 out of the lock-to-the-lock position in the initial upward swing of the pulling lever, substantially as described.

2. In a coupler, a head, a knuckle having a tail, a vertically movable and tilting locking block having a lock-to-the-lock engagement with the coupler head when in locked position, and provided with a lower inclined face, and a tilting and endwise bodily movable pulling lever engaging the knuckle tail and arranged to act upon the inclined face of the locking block to tilt the block out of the lock-to-the-lock position and then lift it by the swinging movement of the pulling lever, substantially as described.

3. In a coupler, a head, a knuckle having a tail, a vertically movable and tilting locking block, the locking block having on its forward and rear sides respectively a lock-to-the-lock and lock-set engagement with the coupler head, and a tilting and endwise bodily movable pulling lever engaging the knuckle tail, said lever extending under the locking block and coöperating with said lock to tilt it and disengage the lock-to-the-lock and lockset it in lifting, substantially as described.

4. In a car coupler, a knuckle having a tail with a shoulder on its lower face, a vertically movable and tilting lock, and a 110 knuckle opener comprising a pulling rod engaging the lower shoulder on the knuckle tail, and thence extending under the knuckle and under the locking block, in combination with a connection arranged to tilt the rod and move it bodily endwise; substantially as described.

5. In a coupler, a knuckle having a tail, a vertically movable and tilting locking block having a beveled lower face, said block being arranged to lockset on the coupler head, and a tilting and endwise bodily movable pulling lever engaging the knuckle tail and extending beneath the locking block, and a connection to tilt and move the lever 125 bodily endwise to act on the inclined or beveled face of the locking block and lift the same and tilt it into lockset position; substantially as described.

6. In a car coupler, a knuckle having a 130

tail, a vertically movable and tilting locking block having a forwardly overhung head and a beveled lower surface, the coupler having a lock-set seat at the rear of the locking block, and a lift device arranged to move the lock vertically and tilt its lower extremity rearwardly on to the rear lock-set seat and its overhung head forwardly to engage the knuckle tail, said lift device directly en-
5 10 gaging the knuckle tail to pull it open; substantially as described.

7. In a car coupler, a knuckle having a tail, a vertically movable and tilting locking block having an over-weighted forwardly projecting head and a depending leg having on its under side a lock-setting surface, the coupler head having a lockset ledge at the rear of the locking block pocket, the knuckle tail being arranged to support the
15 20 head of the block and swing the depending block leg off the lock-set seat, and a tilting and endwise bodily movable pulling lever extending under the lock and arranged to give the leg of the lock an initial rearward movement to lift it and tilt it into lock-set position, substantially as described.

8. In a car coupler, a vertically movable tilting locking block having a projection and recess engagement at its forward side with the coupler to afford a lock-to-the-lock, the locking block having an upper cut-away portion at its rear to allow the block to rest in a rearwardly inclined locking position with the lock-to-the-lock engagement; substantially as described.

9. In a coupler, a head, a knuckle having a tail, a vertically-movable and tilting locking block, and a tilting and bodily endwise-movable pulling lever extending transversely of the coupler head under the block and normally resting in the recess of the floor of the coupler head, entirely below said locking block and out of contact therewith when the locking block is in locked position, substantially as described.

40 45 In testimony whereof, I have hereunto set my hand.

JOHN WILLISON.
